(57) **CLAIM**

We claim, the ornamental design for an outdoor light unit, as shown and described.

DESCRIPTION

FIG. 1 is a side view in elevation of the outdoor light unit, showing our new design;

FIG. 2 is a front view of the outdoor light unit;

FIG. 3 is the opposite side view in elevation of the outdoor light unit as compared to FIG. 1;

FIG. 4 is a top view of the outdoor light unit;

FIG. 5 is a bottom view of the outdoor light unit;

FIG. 6 is a rear view of the outdoor light unit;

FIG. 7 is an enlarged detail of the encircled portion of FIG. 2; and,

FIG. 8 is an enlarged detail of the encircled portion of FIG. 6. Broken lines are shown in the Figures for environmental purposes only and form no part of the claimed design.
